HOLDER FOR MAGNETIC TAPE CASSETTES

Sven Anders Larsson, Frejavagen 3,
172 46 Sundbyberg, Sweden

Filed Apr. 4, 1973, Ser. No. 347,787

Claims priority, application Sweden Oct. 12, 1972

Term of patent 14 years

Int. Cl. D9—99

U.S. Cl. D87—1 D

FIG. 1 is a front perspective view of a holder for magnetic tape cassettes showing my new design;

FIG. 2 is a front elevational view;

FIG. 3 is a top plan view;

FIG. 4 is a left side elevational view;

FIG. 5 is a right side elevational view;

FIG. 6 is a bottom plan view; and

FIG. 7 is a rear elevational view.

I claim:

The ornamental design for a holder for magnetic tape cassettes, as shown.
